UNITED STATES PATENT OFFICE.

WILLIAM G. J. THOMPSON, OF CLINTON, MASSACHUSETTS.

BOTTLE CAP.

Application filed February 19, 1926. Serial No. 89,395.

This invention relates to bottle caps and removers therefor, and has for its object the production of a simple and efficient bottle cap which is provided with means for facilitating the removal of the cap from the bottle, jar, or other receptacle, without the necessity of employing an additional bottle opener or tool.

Another object of this invention is the production of a simple and efficient means for holding the removing device in engagement with the cap.

Other objects and advantages of the present invention will appear throughout the specification and claim.

Figure 1 is a side elevation of a portion of a bottle, showing the cap attached thereto, Figure 2 is a specimen taken on line 2—2 through the cap, the bottle being shown in side elevation, and

Figure 3 is a bottom plan view of the cap. By referring to the drawings, it will be seen that 1 designates the corrugated bottle cap of the usual structure, having the usual crimped edges 2, formed thereon, for the purpose of causing the cap to efficiently grip the upper end 3 of the bottle neck 4. The usual sealing cork 5 is carried within the cap 1 and a cap removing device 5' is employed constituting a fabric loop having its free ends securely fitted between the sealing cork 5 and the inner face of the cap 1, as clearly shown in Figure 2. The edge of the sealing cork as indicated at 6, is adapted to bind the removing device 5' in engagement with the inwardly turned flange or crimped portion 2 of the cap 1, as is clearly illustrated in Figure 2.

From the foregoing description it will be seen that a very simple and efficient device has been produced in the nature of a cape-like device, the free ends are clamped firmly between the sealing cork 5 and the cap 1, the loop portion thereof indicated by the numeral 7 being adapted to extend down along the neck of the bottle for the purpose of permitting an operator to grip the loop 7, and by pulling the same upwardly the cap 1 will be forced out of engagement with the upper end of the neck of the bottle, thereby removing the cap from the bottle.

It should be understood that certain detailed changes in the mechanical structure may be made without departing from the spirit of the invention, so long as these changes fall within the scope of the appended claim.

Having described the invention what is claimed is:—

The combination with a bottle cap having a sealing cork fitted therein, of a fabric tape folded back upon itself with the terminals placed one upon the other and secured between the cap and sealing cork, said terminals extending diametrically across the cap and terminating short of one side thereof, the major portion of the tape extending beyond the edges of said cap defining a flexible pulling loop, said loop constituting a finger grip for permitting the operator to engage the loop between fingers whereby to facilitate the removal of the cap from the neck of a bottle.

In testimony whereof I affix my signature.

WILLIAM G. J. THOMPSON.
